CLAIM

The ornamental design for a portable drinking device, as shown and described.

DESCRIPTION

FIG. 1 is a left, front perspective view of a portable drinking device, shown in environmental use, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines in FIGS. 1-7 show portions of the drinking device and form no part of the claimed design. The broken lines forming the can in FIG. 1 are for the purpose of illustrating environment only and form no part of the claimed design.

1 Claim, 4 Drawing Sheets
